United States Patent Office

Des. 201,100
Patented May 11, 1965

201,100

METER

Arthur J. Little, Frank A. Ryder, and Charles A. Woodcock, Springfield, Ill., assignors to Stewart-Warner Corporation, Chicago, Ill., a corporation of Virginia

Filed Feb. 12, 1964, Ser. No. 78,607

Term of patent 14 years

(Cl. D52—6)

FIG. 1.

FIG. 2.

FIG. 1 is a perspective view taken from the front and to one side of a meter embodying our new design, and FIG. 2 is an elevational view taken from the front of the meter shown in FIG. 1.

The undisclosed side of the meter is substantially the same in appearance as the side shown. The rear of the meter is substantially plain in appearance, and the bottom is substantially the same in appearance as the top.

We claim:

The ornamental design for a meter, substantially as shown and described.
